US0D1073960S

(12) **United States Design Patent** (10) **Patent No.:** **US D1,073,960 S**
(45) **Date of Patent:** **** May 6, 2025**

(54) **LEG AND FOOT ELEVATOR DEVICE**

(71) Applicant: **David Elliot Shaffer**, Great Neck, NY (US)

(72) Inventor: **David Elliot Shaffer**, Great Neck, NY (US)

(**) Term: **15 Years**

(21) Appl. No.: **29/839,015**

(22) Filed: **May 17, 2022**

(51) **LOC (15) Cl.** **24-02**

(52) **U.S. Cl.**

USPC **D24/190; D6/601**

(57) **CLAIM**

The ornamental design for a leg and foot elevator device, as shown and described.

DESCRIPTION

FIG. 1 is a front-top-right view of a leg and foot elevator device showing my new design;

FIG. 2 is a rear-bottom-left view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

1 Claim, 8 Drawing Sheets
